INDICATOR PANEL FOR A SECURITY ALARM SYSTEM PORTABLE DEMONSTRATOR UNIT

James F. Pinkham, Kensington, Md., assignor to
Multra-Guard, Inc., Rockville, Md.

Filed Feb. 5, 1970, Ser. No. 21,296

Term of patent 14 years

Int. Cl. D29—99

U.S. Cl. D72—1

FIG. 1

FIG2

FIG3

FIG4

FIG5

FIG. 1 is a front elevational view of an indicator panel for a security alarm system portable demonstrator unit showing my new design, the back being substantially planar;

FIG. 2 is an edge elevation view thereof in the direction of arrow 2 in FIG. 1;

FIG. 3 is an edge elevation view thereof in the direction of arrow 3 in FIG. 1;

FIG. 4 is an edge elevation view thereof in the direction of arrow 4 in FIG. 1; and

FIG. 5 is an edge elevation view thereof in the direction of arrow 5 in FIG. 1.

The broken lines shown in FIG. 1 are for illustrative purposes only, and form no part of the claimed design.

I claim:

The ornamental design for an indicator panel for a security alarm system portable demonstrator unit, substantially as shown and described.
